UNITED STATES PATENT OFFICE.

CARL H. ZWERMANN, OF KALAMAZOO, MICHIGAN.

KILN.

1,306,161.

Specification of Letters Patent. Patented June 10, 1919.

Application filed September 11, 1918. Serial No. 253,536.

To all whom it may concern:

Be it known that I, CARL H. ZWERMANN, a citizen of the United States, residing at the city and county of Kalamazoo, State of Michigan, have invented certain new and useful Improvements in Kilns, of which the following is a specification.

This invention relates to improvements in kilns.

10 The main objects of this invention are:

First, to provide a kiln in which fuel saving is accomplished by the utilization to a very large extent of the heat given off by the cooling stock to partially heat the incoming

15 stock.

Second, to provide in a kiln an improved air heating and circulating means in a pre-heating zone.

20 Third, to provide a kiln in which a large portion of the heat units in the products of combustion or waste gases are utilized.

Fourth, to provide a kiln in which the firing as well as preheating is accomplished by means of circulating air, the stock treated 25 being at no time subject to the products of combustion.

Fifth, to provide an improved kiln in which the walls of the combustion chamber are supported so that the expanding or contracting thereof does not injuriously affect 30 other parts of the structure.

Sixth, to provide an improved kiln which is of large capacity.

Further objects, and objects relating to 35 structural details, will definitely appear from the detailed description to follow.

I accomplish the objects of my invention by the devices and means described in the following specification. The invention is 40 clearly defined and pointed out in the claims.

A structure which is a preferred embodiment of my invention is clearly illustrated in the accompanying drawing, forming a part of this specification, in which:

45 Figure I and Fig. I^A are complementary detail vertical longitudinal sections through one of the tunnels of my improved kiln on a line corresponding to line 1—1 of Figs. III and III^A.

50 Fig. II and Fig. II^A are complementary detail longitudinal sections through my improved kiln on a line corresponding to line 2—2 of Figs. III and III^A.

55 Fig. III and Fig. III^A are complementary detail horizontal sections through my im-

proved kiln on a line corresponding to line 3—3 of Figs. I, I^A, II, and II^A.

Fig. IV is a transverse vertical section on a line corresponding to line 4—4 of Figs. I, II and III.

60 Fig. V is a transverse vertical section on a line corresponding to line 5—5 of Figs. III and III^A.

Fig. VI is an enlarged detail vertical transverse section on a line corresponding to 65 line 6—6 of Figs. III and III^A.

Fig. VII is an enlarged detail transverse section on a line corresponding to line 7—7 of Figs. III and III^A.

Fig. VIII is a detail longitudinal section 70 on a line corresponding to line 8—8 of Figs. III and III^A.

Fig. IX is an enlarged detail longitudinal section on a line corresponding to line 9—9 of Figs. III, III^A and V.

75 Fig. X is a vertical central section through one of the preliminary heating zones and cooling zone flues.

Fig. XI is a detail longitudinal section on a line corresponding to line 11—11 of Figs. 80 III and III^A.

Fig. XII is a plan view of one of the trucks.

Fig. XIII is a detail vertical section through the bed thereof on a line corresponding to line 13—13 of Fig. XII.

85 In the drawing similar reference characters refer to similar parts throughout the several views and the sectional views are taken looking in the direction of the little arrows at the ends of the section lines.

90 Referring to the drawing, I provide a pair of tunnels, designated generally by the numerals 1 and 2, the tunnels being substantial duplicates and are arranged side by side but in a reverse relation, the discharging end of one tunnel being at the charging end of the other, as is the case in the structure shown in Letters Patent, issued to me Aug. 13, 1918, No. 1,275,353. The inner wall 3 of the tunnels is common to both.

95 A transfer track 4 is arranged at each end of the tunnels. The kilns shown are designed for the burning of liquid or gaseous fuel, a burner B being conventionally illustrated,—see Fig. VIII. Only slight modification and adaptation is required to adapt the structure to the burning of solid fuels.

100 The trucks 5 are shown conventionally,

tracks 6 being provided in each tunnel. A propelling mechanism, designated generally by the numeral 7, is provided at the charging end of each tunnel, the charging mechanism being driven by a mechanism designated by the numeral 8, the purpose being to provide a substantially continuous movement of the trucks through the kilns. The trucks 5 are provided with beds comprising 5 a top having holes 9 therein and circulating passages 10 opening at the sides of the trucks so that the air may circulate through the passages 10 and up through the openings 9 so that uniform heating of the stock is secured. Each tunnel is provided with a 10 combustion chamber 11 at the outer side of its firing zone.

The walls 12 of the combustion chamber are preferably formed of relatively thin 20 plates of carborundum and are capable of withstanding great heat and at the same time are relatively thin so that the heat is readily transmitted thereto. These combustion chamber wall plates 12 are supported 25 by spaced transverse ribs 13 in the walls at the bottom and sides of the combustion chamber forming a series of circulating passages 14 surrounding the combustion chamber and opening into the firing zone of the 30 tunnel,—see Figs. III, III^A, V and VIII.

A baffle wall 15 is provided between the tunnel chamber and the combustion chamber so as to compel a circulation from these flues or circulating passages 14 through the tunnel chamber,—see Fig. V. The trucks are of such height that their circulating passages 10 are in alignment with the openings 16 communicating with the bottoms of the passages 14,—see Fig. V. With this arrangement of parts the firing zone may be 40 suitably heated without any of the products of combustion coming into contact with the stock treated.

Each combustion chamber discharges to a 45 preheating flue 17 extending for some distance along the outer side of each tunnel toward the entrance or charging end thereof to the stacks 18. The inner walls 15' of the preheating flues are continuations of the 50 baffle walls 15.

The bottom plates 19 of these preheating flues are supported by spaced ribs 20 providing passages 21 opening into the tunnel chambers on a level with the passages 10 of 55 the truck bed,—see Fig. V. Air circulating flues 22, preferably of metal, open through the bottom plates 19 to communicate with these passages 21 and through the top plates 23 into a space 24 above the preheating flues. 60 This secures a large radiating surface for the preheating flues and insures a circulation of air in the preheating zone.

In advance of each preheating zone is the "water smoking" zone as it is called sometimes in which the cooling of the stock in the

discharging end of one tunnel is utilized to preliminarily heat the ware in the other tunnel and vice versa. The inner wall 3, preferably has thin portions 3' at this point and a series of vertically disposed circulating flues 25 are arranged in the discharging or cooling end of the tunnels, and provided with lateral arms 26 at the top and bottom openings through the inner wall into the other tunnel,—see Figs. III, 111^A, VI and X. 70 This provides heat for the "water smoking" step and also facilitates the cooling of the discharge.

To provide preheated air for the burners I provide a passage 27 in the top of each 80 tunnel opening to the outer air at 28, the passages being provided with a vertical portion 29 in the outer wall leading to the burners. The water smoking zone of each tunnel is provided with vents 30. By this arrangement the stock is gradually heated without bringing the products of combustion into contact with it at any time and an effective circulation is secured in the "water smoking" zone, preheating zone and the firing zone, so that the stock not only is uniformly heated but all of the stock is effectively heated and fired without regard to its position on the truck and this circulation is maintained without the employment 90 of fans or the like.

The combustion chamber illustrated is well adapted for the use of liquid or gaseous fuel but may be used for solid fuel substantially without change. It is of relatively 100 large dimensions which allows for the full development of the flame in quite a restricted zone, thereby securing the highest heat or firing zone in a comparatively restricted area, where it is needed and desired.

I have illustrated and described my present improvements in an embodiment which I consider highly desirable. I have not attempted to illustrate or describe certain modifications or adaptations which I contemplate as I believe the disclosure made will enable those skilled in the art to which my invention relates to embody or adapt the same as may be desired.

Having thus described my invention, what 115 I claim as new and desire to secure by Letters Patent, is:

1. The combination of a pair of tunnel kilns disposed in reverse relation with the charging end of one at the discharging end 120 of the other and having a common inner wall, heating means comprising combustion chambers disposed at the outer sides of the tunnels, baffle walls between the tunnel chambers and combustion chambers disposed 125 with their tops in a spaced relation to the tops of the tunnel chambers and having openings therethrough at the bottom, said combustion chambers being formed of plates supported by spaced transverse ribs on the 130

- walls at the sides and bottom thereof providing air circulating passages communicating with the tunnel chambers through said openings in said baffle walls and over the tops 5 thereof, preheating flues to which the combustion chambers deliver, the inner walls for the preheating flues being continuations of said baffle walls, there being spaced transverse passages below said preheating flues 10 communicating with the tunnel chambers, vertical air circulating flues disposed through said preheating flues with their lower ends opening into said passages below the same and their upper ends communicating 15 with the tunnel chambers, said combustion chambers and preheating flues being disposed in reverse relation with the preheating flues toward the charging ends of the tunnels, circulating flues disposed at the 20 inner sides of the discharge ends of the tunnels and opening at their upper and lower ends through the inner wall of the tunnels into the ends of the tunnels, and air preheating passages for the heating means 25 formed in the top walls of the tunnels and leading from the discharge ends thereof and having delivery portions in the outer walls of the tunnels communicating with the heating means.
- 30 2. The combination of a pair of tunnel kilns disposed in reverse relation with the charging end of one at the discharging end of the other and having a common inner wall, heating means comprising combustion chambers disposed at the outer sides of the tunnels, baffle walls between the tunnel chambers and combustion chambers disposed with their tops in a spaced relation to the tops of the tunnel chambers and having openings therethrough at the bottom, said combustion 35 chambers being formed of plates supported by spaced transverse ribs on the walls at the sides and bottom thereof providing air circulating passages communicating with the tunnel chambers, vertical air circulating flues disposed through said preheating flues with their lower ends 40 opening into said passages below the same and their upper ends communicating with the tunnel chambers, said combustion chambers and preheating flues being disposed in reverse relation with the preheating flues toward the charging ends of the tunnels, and air preheating passages for the heating means formed in the top walls of the tunnels and leading from the discharge ends thereof 45 and having delivery portions in the outer walls of the tunnels communicating with the heating means.
- 40 4. The combination of a pair of tunnel kilns disposed in reverse relation with the charging end of one at the discharging end of the other having a common inner wall, heating means comprising combustion chambers disposed at the outer sides of the tunnels, baffle walls between the tunnel chambers and combustion chambers disposed with their tops in a spaced relation to the tops of the tunnel chambers and having openings therethrough at the bottom, said combustion 45 chambers being formed of plates supported by spaced transverse ribs on the walls at the sides and bottom thereof providing air circulating passages communicating with the tunnel chambers through said openings in said baffle walls and over the tops thereof, preheating flues to which the combustion chambers deliver, the inner walls for the preheating flues being continuations of said baffle walls, there being spaced transverse 50 passages below said preheating flues communicating with the tunnel chambers, vertical air circulating flues disposed through said preheating flues with their lower ends opening into said passages below the same and their upper ends communicating with the tunnel chambers, said combustion chambers and preheating flues being disposed in reverse relation with the preheating flues toward the charging ends of the tunnels, and circulating flues disposed at the inner sides of the discharge ends of the tunnels and opening at their upper and lower ends through the inner wall of the 55 tunnels into the ends of the tunnels.
- 50 3. The combination of a pair of tunnel kilns disposed in reverse relation with the charging end of one at the discharging end of the other having a common inner wall, heating means comprising combustion chambers disposed at the outer sides of the tunnels, baffle walls between the tunnel chambers and combustion chambers disposed with their tops in a spaced relation to the tops of the tunnel chambers and having openings therethrough at the bottom, said combustion 55 chambers being formed of plates supported by spaced transverse ribs on the walls at the sides and bottom thereof providing air circulating passages communicating with the tunnel chambers through said openings in said baffle walls and over the tops thereof, preheating flues to which the combustion chambers deliver, the inner walls for the preheating flues being continuations of said baffle walls, there being spaced transverse 60 passages below said preheating flues communicating with the tunnel chambers, vertical air circulating flues disposed through said preheating flues with their lower ends opening into said passages below the same and their upper ends communicating with the tunnel chambers, said combustion chambers and preheating flues being disposed in reverse relation with the preheating flues toward the charging ends of the tunnels, and circulating flues disposed at the inner sides of the discharge ends of the tunnels and opening at their upper and lower ends through the inner wall of the 65 tunnels into the ends of the tunnels.

tion chambers and preheating flues being disposed in reverse relation with the preheating flues toward the charging ends of the tunnels.

- 5 5. The combination of a pair of tunnel kilns disposed in reverse relation with the charging end of one at the discharging end of the other and having a common inner wall, heating means comprising combustion chambers disposed at the outer sides of the tunnels, baffle walls between the tunnel chambers and combustion chambers, air circulating passages about said combustion chamber communicating at their upper and 15 lower ends with the tunnel chambers, preheating flues to which the combustion chambers deliver, inner walls for the preheating flues being continuations of said baffle walls, air circulating flues disposed through said 20 preheating flues and communicating at their upper and lower ends with said tunnel chambers, said combustion chambers and preheating flues being disposed in reverse relation with the preheating flues toward the charging 25 ends of the tunnels, and circulating flues disposed at the inner sides of the discharge ends of the tunnels and opening at their upper and lower ends through the inner wall of the tunnel into the charging end of 30 the tunnels.

6. The combination of a pair of tunnel kilns disposed in reverse relation with the charging end of one at the discharging end of the other having a common inner wall, heating means comprising combustion chambers disposed at the outer sides of the tunnels, baffle walls between the tunnel chambers and combustion chambers, air circulating passages about said combustion chamber communicating at their upper and lower ends with the tunnel chambers, preheating flues to which the combustion chambers deliver, inner walls for the preheating flues being continuations of said baffle walls, and 40 air circulating flues disposed through said preheating flues and communicating at their upper and lower ends with said tunnel chambers, said combustion chambers and preheating flues being disposed in reverse relation with the preheating flues toward the charging 45 ends of the tunnels.

7. The combination of a pair of tunnel kilns disposed in reverse relation with the charging end of one at the discharging end of the other and having a common inner wall, heating means comprising combustion chambers disposed at the outer sides of the tunnels, air circulating passages about said combustion chamber communicating at their 55 upper and lower ends with the tunnel chambers, preheating flues to which the combustion chambers deliver, air circulating flues disposed through said preheating flues and communicating at their upper and lower 60 ends with said tunnel chambers, said com-

bustion chambers and preheating flues being disposed in reverse relation with the preheating flues toward the charging ends of the tunnels, and circulating flues disposed at the inner sides of the discharge 70 ends of the tunnels and opening at their upper and lower ends through the inner wall of the tunnel into the charging end of the tunnels.

8. The combination of a pair of tunnel kilns disposed in reverse relation with the charging end of one at the discharging end of the other having a common inner wall, heating means comprising combustion chambers disposed at the outer sides of the tunnels, air circulating passages for said combustion chambers communicating with the tunnel chambers, preheating flues to which the combustion chambers deliver, air circulating flues for said preheating flues communicating with said tunnel chambers, said combustion chambers and preheating flues being disposed in reverse relation with the preheating flues toward the charging ends of the tunnels, and air circulating flues disposed in the discharge end of one tunnel and 80 communicating with the charging end of the other tunnel. 90

9. The combination of a pair of tunnel kilns disposed in reverse relation with the charging end of one at the discharging end of the other having a common inner wall, heating means comprising combustion chambers disposed at the outer sides of the tunnels, air circulating passages for said combustion chambers communicating with the tunnel chambers, preheating flues to which the combustion chambers deliver, and air circulating flues for said preheating flues communicating with said tunnel chambers, said combustion chambers and preheating flues being disposed in reverse relation with the preheating flues toward the charging 100 ends of the tunnels. 105

10. The combination of a pair of tunnel kilns disposed in reverse relation with the charging end of one at the discharging end of the other and having a common inner wall, heating means disposed centrally of the tunnels, and circulating flues comprising vertical pipes disposed at the inner sides of the discharge ends of the tunnels and opening at their tops and bottoms through the inner wall and delivering to the tops and bottoms of the charging ends of the tunnels. 110 115

11. The combination of a pair of tunnel kilns disposed in reverse relation with the charging end of one at the discharging end of the other, heating means centrally of the tunnels, preheating means disposed in advance of the heating means to receive the products of combustion therefrom, and air circulating flues comprising vertical pipes disposed in the discharge end of one tunnel 120 125 130

and communicating with the charging end of the other tunnel.

12. The combination of a pair of tunnel kilns disposed in reverse relation with the 5 charging end of one at the discharging end of the other, heating means centrally of the tunnels, and air circulating flues comprising vertical pipes disposed in the discharge end of one tunnel and communicating with the 10 charging end of the other tunnel.

13. The combination of a tunnel kiln, heating means comprising a combustion chamber disposed at the side of the tunnel chamber, a baffle wall between the tunnel 15 chamber and combustion chamber disposed with its top in a spaced relation to the top of the tunnel chamber and having openings therethrough at the bottom, said combustion chamber being formed of plates supported 20 by spaced transverse ribs on the walls at the sides and bottom thereof providing air

circulating passages communicating with the tunnel chamber through said openings in said baffle wall and over the top thereof, a preheating flue to which the combustion 25 chamber delivers, the inner wall for the pre-heating flue being a continuation of said baffle wall, there being spaced transverse passages below said preheating flue communicating with the tunnel chamber, vertical 30 air circulating flues disposed through said preheating flue with their lower ends opening into said passages below the same and their upper ends communicating with the tunnel chamber.

In witness whereof, I have hereunto set my hand and seal in the presence of two witnesses.

CARL H. ZWERMANN. [L. s.]
